Primary Examiner—George P. Word

[57] CLAIM

The ornamental design for a drink cup holder for an automobile, as shown and described.

DESCRIPTION

FIG. 1 is a perspective view of a drink cup holder for an automobile showing my new design;

FIG. 2 is a right side elevational view thereof;

FIG. 3 is a front elevational view thereof;

FIG. 4 is a rear elevational view thereof; and

FIG. 5 is a bottom plan view thereof.

FIG. 1

FIG. 3
